GRINDING WHEEL DRESSING MECHANISM

Stanford P. Bruce, Detroit, Mich., assignor to
 Wheel Trueing Tool Company, Detroit, Mich.,
 a corporation of Delaware

Application April 29, 1947, Serial No. 744,749

8 Claims. (Cl. 125—11)

1

This invention relates to new and useful improvements in tool holders of the type conventionally used for dressing grinding wheels and the like.

All grinding wheels must be dressed from time to time as the cutting faces become worn in order to maintain a proper cutting action. Dressing usually is accomplished by moving a diamond back and forth across the periphery of the wheel as the latter is rotated about its axis. The diamond is mounted in a suitable holder which holds it steady and at a proper angle to the wheel and suitable means may be provided for rotating the holder periodically to prevent the diamond from being worn unevenly.

Working clearances necessary for rotation of the diamond holder frequently permit the rotatable parts to chatter or vibrate; and when this occurs the surface of the grinding wheel is left rough and unfit for accurate work. All efforts to arrange the parts of the dressing mechanism in such manner that the diamond holder can be rotated without attendant destructive chattering have for the most part been unsuccessful. This problem is a very real one and has long been recognized by workers in the art.

In certain standard grinding machines such as Cincinnati grinders, the dressing mechanism is mounted in a confined space behind the grinding wheel. In this case, the problem of providing rotation without vibration is further complicated by the fact that the diamond holder must be mounted and operated in a limited space.

An important object of the present invention is to provide a dressing mechanism for grinding wheels wherein the diamond holder is mounted for rotation and in such manner that chattering or vibration is substantially entirely eliminated.

Another object of the invention is to provide a wheel dressing mechanism of the above mentioned character wherein the parts are compactly arranged and preeminently suited for use on grinders of the Cincinnati type.

Still another object of the invention is to provide a wheel dressing mechanism of the above mentioned character having a novel means for imparting step-by-step rotation to the diamond holder.

Yet another object of the invention is to provide a wheel dressing mechanism that is simple in construction, efficient in operation and relatively inexpensive to manufacture.

Other objects and advantages of the invention will be apparent during the course of the following description.

2

In the drawing forming a part of this specification and wherein like numerals are employed to designate like parts throughout the same:

Fig. 1 is a fragmentary end elevational view of 5 a conventional grinding machine having a wheel dressing mechanism embodying the present invention associated therewith, parts of the grinder being broken away and shown in section for clearness of illustration;

Fig. 2 is an enlarged view of the portion of 10 Fig. 1 enclosed in the circle 2, parts being shown in elevation and parts in section to more clearly illustrate the working parts of the wheel dressing mechanism;

Fig. 3 is an enlarged, fragmentary, longitudinal 15 section view taken on the line 3—3 of Fig. 2;

Fig. 4 is a fragmentary perspective view of a 20 portion of the grinding wheel and its adjuncts and particularly illustrating a preferred means for imparting intermittent or step-by-step rotation to the diamond holder;

Fig. 5 is an enlarged, fragmentary, vertical 25 sectional view taken on the line 5—5 of Fig. 4;

Fig. 6 is a fragmentary, longitudinal sectional 30 view through the wheel dressing mechanism;

Fig. 7 is a fragmentary, transverse sectional 35 view taken on the line 7—7 of Fig. 6;

Fig. 8 is a fragmentary, longitudinal sectional 40 view through a modified wheel dressing mechanism embodying the invention; and

Fig. 9 is a transverse sectional view taken on 45 the line 9—9 of Fig. 8.

In the drawing, the wheel dressing mechanism embodying the present invention is shown 35 associated with a Cincinnati grinder of the type having a rotatably driven grinding wheel 10 shielded by a guard 12. Behind the guard 12 is a generally horizontal table 14 which supports the usual slide 16 for reciprocatory movement 40 parallel to the axis of grinding wheel 10. Slide 16 carries a wheel dressing mechanism which extends forwardly through the guard 12 to position a diamond nib in operative association with the working face or periphery of the grinding 45 wheel 10.

The above set-up is conventional and is given 50 merely to provide an operative setting for the wheel dressing mechanism of the present invention. A Cincinnati type grinder was selected because it is typical of those grinders which allow only slight space at or adjacent to the surface of the wheel in which the wheel dressing mechanism must operate. By reason of the unique 55 manner in which the parts are combined and co-related, the mechanism of this invention, is admirably suited for grinders of the Cincinnati type.

In this connection, however, it is to be understood that the wheel dressing mechanism is not limited in its use to grinders of the type here shown. It can be adapted readily for any type of grinder, and it can be used in any capacity where a device of this character has utility.

Considered in certain of its broader aspects, the wheel dressing mechanism embodying the present invention comprises a carrier 18 which is adapted for attachment to the slide 16 and rotatably mounts the tool holder 20. As best shown in Fig. 2, carrier 18 forms a case which encloses the rear portion of tool holder 20, and the latter projects forwardly from the end of said carrier toward the grinding wheel 10. A diamond tool 22 set into a socket 23 provided in the forward end of the holder 20 carries the usual diamond 24, and the slide 16 is advanced or retracted in the conventional manner to position the diamond for proper engagement with the peripheral face of grinding wheel 10 when said slide 16 is within that portion of its traversing movement which corresponds with the width of said peripheral face of the grinding wheel.

In the form of the invention shown in Figs. 1-7, intermittent, step-by-step rotation is imparted to the holder 20 by a ratchet 26 which is mounted on the projecting forward portion of the holder and extends radially beyond the carrier 18 for engagement with an actuator or pawl 28 on the guard 12. When the slide 16 is moved in one direction on table 14 during the dressing operation, ratchet 26 is pushed against the pawl 28 and the latter rotatably actuates the ratchet and its adjuncts. As best shown in Figure 4, the ratchet 26 is actuated by pawl 28 secured to guard 12 at the completion of the traverse of the dressing tool across the face of the grinding wheel and while the dressing tool is out of contact with the grinding wheel. When the slide 16 is retracted, pawl 28 passes freely over the teeth of the ratchet 26.

In this manner, step-by-step rotation is imparted to the tool holder 20 and after each operation of the slide the diamond 24 presents a fresh, sharp cutting edge to the grinding wheel 10. Since ratchet 26 is rotated continuously in the same direction, the diamond 24 is worn evenly and its working life is substantially extended.

Preferably, a detent mechanism also is provided for controlling rotative movement of the tool holder 20 and for preventing the pawl 28 from inadvertently rotating ratchet 26 in a reverse direction.

More specifically, the carrier 18 comprises a generally circular case 30 having a suitable cover 32 fastened thereto by an annular series of screws 34 or the like. A rearwardly extending shank 36 is formed on the case 30, which shank enters a socket 38 in the end of slide 16 and is secured by a set screw 40. Thus, the carrier 18 is fixably associated with the slide 16 and is movable therewith as the latter slides back and forth on the table 14.

The case 30 and cover 32 define a generally circular chamber 42 within the carrier 18 and the tool holder 20 extends into the chamber through a central opening 44 in the cover. At the rearward end thereof, the tool holder 20 is formed with a radially extending, annular flange 46 which seats solidly against the rear face of chamber 42 and fits snugly within the annular surrounding wall of the chamber. It will be observed that the front radial face of flange 46 is spaced from the front wall of chamber 42 and

that an annular spring element 48 is confined therebetween. The spring element 48 here shown is an annular, undulating strip of spring metal which engages the flange 46 and cover 32 at circumferentially spaced points, as shown in Fig. 3; and this element normally is compressed to yieldably force the holder 20 rearwardly against the carrier 18. A washer 50 preferably is interposed between flange 46 and the spring 48.

From the foregoing, it will be readily apparent that chamber 42 provides a broad flat surface behind the tool holder 20 and that the latter is pressed solidly against this surface by the spring 48. Also, the annular surrounding wall of the chamber snugly fits the periphery of flange 46 to additionally support and stabilize the holder 20. In actual practice, I have found that this unique combination and correlation of parts is efficacious to prevent destructive vibration or chattering of the tool holder 20 in the carrier 18 during the critical dressing operation; and, at the same time, the tool holder is free to rotate in the carrier. Thus, by reason of the instant construction, I am able to mount the tool holder for rotation; and, at the same time, have eliminated the destructive chattering and vibration which heretofore has inevitably accompanied a rotatable mounting.

It is desirable to position the rear bearing surface of the tool holder 20 as close to the diamond point 24 as possible in order to reduce the effect of such minor vibration as may occur. Further, it is desirable that the assembly as a whole be compact in order that it may be used with grinders such as the Cincinnati grinder shown in the drawing.

Ratchet 26 conveniently may be fastened to the tool holder 20 by a radial set screw 52 (Fig. 2) and it preferably is disposed against and supported by the carrier 18. The pawl 28 is in the form of an elongated bar which is hinged to a support 54, as best shown in Fig. 4. One end of support 54 is pivoted to a mounting block 56 on the guard 12 and the other end thereof is pivoted to a linkage 58, which linkage also is attached to the mounting block 56 and is adjustable to effect a proper engagement between the pawl and ratchet 26. As shown in Fig. 5, the support 54 carries a stop 60 which extends along one side of the pawl 28 and prevents the same from swinging in one direction about its pivots.

Thus, when the wheel dressing mechanism is moved in one direction, on the table 14, pawl 28 is positioned by stop 60 to engage the teeth of ratchet 26 so as to rotate the tool holder 20 and diamond tool 22. However, on the return stroke of the dressing mechanism, pawl 28 pivots freely to substantially the dotted line position in Fig. 5, in which position it rides over the teeth of ratchet 26 without rotating the same. In this manner, ratchet 26 and its adjuncts are continuously rotated in one direction by successive translatory movements of the wheel dressing assembly.

In order to control rotation of tool holder 20, the flange 46 is provided with a radial bore 62 and a ball detent 64 is disposed in the bore. A coil spring 66 confined in bore 62 behind the ball detent 64 continuously urges the latter radially outwardly against the annular surrounding wall of chamber 42 and into sockets 68 which are provided at spaced intervals around the wall.

Each operation of the tool holder 20 by the pawl and ratchet mechanism hereinabove described causes the ball detent 64 to move from one socket 68 to the adjacent socket, and suc-

sive operations of the mechanism causes the ball detent to move progressively from one socket to another. In this manner, the diamond 24 is identically positioned each time the ball detent 64 is in a particular socket 68. As a result, the diamond assumes the shape of a polysided pyramid and maintains the same shape regardless of the number of rotations made by the diamond holder 20. By wearing the diamond 24 in this manner, the edges between adjacent facets are maintained in a sharp condition at all times and a fresh, sharp cutting edge is presented to the grinding wheel 10 after each operation of the pawl and ratchet mechanism.

Attention is now directed to Figs. 8 and 9 which show a modified pawl and ratchet mechanism for rotating the tool holder 20. In this form of the invention, the tool holder 20 is provided with a rearwardly extending hub 70 and the bore 23 which receives the diamond tool 22 extends entirely through the holder. The chamber 42 in carrier 18 is formed with a centrally located recess or a socket 74 which accommodates the hub 70 and the shank 36 is formed separately as perhaps best shown in Fig. 8. Shank 36 has a radial flange 16 which fits snugly in socket 74 and abuts the rear face of the holder 20. Also, shank 36 is formed with an axially extending centrally located head 78 which projects forwardly of flange 16 and seats snugly in the bore 23 to support the rear portion of the tool holder 20 for rotation.

Fixed on the hub 70 is a ratchet 80 which contacts with a pawl 82 to rotate the tool holder 20. If desired, the ratchet 80 may be a separate element on the tool holder, but it preferably is formed integrally therewith as shown in Fig. 9. Also, it will be observed that in this form of the invention, the pawl 82 is carried by a plunger 84 which is slidably mounted in the carrier 18 and is arranged tangentially to the ratchet 80. A spring 86 ahead of plunger 84 urges the latter normally to a retracted position in the carrier 18. At one end of the plunger 84 is a longitudinal shank 88 which projects from the carrier 18 for actuation by suitable stop or abutment (not shown), as will be readily understood by those skilled in the art.

In operation, the latter form of the invention is substantially identical to the form first described and the same advantages obtain in both forms of the invention. When slide 16 is moved in one direction on the table 14, the shank 88 engages a suitably positioned stop or abutment to advance the plunger 84 and move pawl 82 against ratchet 80. On the return stroke of slide 16, spring 86 automatically retracts the plunger 84 and pawl 82. The parts then occupy the initial position and are ready for another cycle of operation. Each time the pawl and ratchet mechanism operates, the diamond 24 is turned angularly to present a fresh sharp cutting edge to the grinding wheel 10.

It is to be understood that the forms of the invention herewith shown and described are to be taken as preferred examples of the same and that various changes in the size, shape and arrangement of the parts may be resorted to without departing from the spirit of the invention or the scope of the appended claims.

Having thus described the invention, I claim:

1. In a grinding wheel dressing assembly including a housing, a reciprocable carriage movable along said housing, a rotatable tool holder on said carriage having its axis perpendicular to the line of movement of said carriage, said tool

holder having a radially projecting, annular flange; a carrier for said holder shaped to provide a seat for the rear radial surface of said flange and having an annular surrounding surface around the periphery of said flange, said annular surface having a plurality of circumferentially spaced sockets; detent means carried by said flange and projecting radially therefrom to seat successively in said sockets upon rotation of the tool holder; spring means about said holder urging said flange pressed solidly against its seat; and ratchet means on said holder for rotating the tool holder in said carrier.

2. The combination as set forth in claim 1 wherein said spring means comprises an annular undulating strip of spring metal confined between the forward radial face of the flange and said carrier.

3. In a grinding wheel dressing assembly, a rotatable tool holder having a radially projecting, annular flange; a carrier for said holder having a seat for the rear radial surface of said flange and an annular surface around the periphery of said flange, said annular surface having a plurality of circumferentially spaced sockets; detent means carried by said flange and projecting radially therefrom to seat successively in said sockets upon rotation of the tool holder; spring means about said holder holding said flange pressed solidly against its seat; a ratchet fixed on the tool holder; a slide on which the carrier and its adjuncts are reciprocated in a direction parallel to the plane of said ratchet; and a stationary pawl mounted at one end of the reciprocatory travel of said carrier to engage the ratchet during reciprocation of the carrier and adapted to impart a step-by-step rotation to the tool holder.

4. In a grinding wheel dressing assembly, a rotatable tool holder having a radially projecting annular flange; a carrier for said holder having a seat for the rear radial surface of said flange and an annular surface around the periphery of said flange, said annular surface having a plurality of circumferentially spaced sockets, detent means carried by said flange and projecting radially therefrom to seat successively in said sockets upon rotation of the tool holder; spring means about said holder holding said flange pressed solidly against its seat; a ratchet fixed on the tool holder and projecting radially beyond the carrier; a slide on which the carrier is bodily reciprocated in a direction transverse to the axis of said ratchet; and a stationary pawl positioned at one end of the reciprocatory travel of said carrier to engage said ratchet during reciprocation of the carrier whereby to impart a step-by-step rotation to said tool holder.

5. In combination, a machine grinder having a rotatably driven grinding wheel; and a wheel dressing mechanism mounted for translatory movement parallel to a surface of the grinding wheel to be dressed, said wheel dressing mechanism including a rotatable tool holder having a radially projecting annular flange, a carrier for said holder having a seat for the rear radial surface of said flange and an annular surface around the periphery of said flange, said annular surface having a plurality of circumferentially spaced sockets, detent means carried by said flange and projecting radially therefrom to seat successively in said sockets upon rotation of the tool holder, spring means holding said flange pressed solidly against the seat, a ratchet fixed on the tool holder and projecting radially beyond

the carrier, and a stationary pawl positioned at an end of said translatory movement to engage said ratchet each time relative bodily movement occurs between the wheel dressing mechanism and said grinding wheel, whereby automatically to impart a step-by-step rotation in one direction to said tool holder.

6. In a grinding wheel assembly including a wheel rotatably mounted about its axis, a guard around said wheel, a slide mounted for reciprocation along said guard in a line of traverse parallel to the axis of said wheel and across the peripheral face thereof, said slide being also mounted for advancement toward and retraction away from said peripheral face and having a forward end facing and proximate to said peripheral face when said slide is advanced and is within that portion of its traversing movement corresponding to the width of said peripheral face, a holder for a diamond tool on said slide mounted for rotation about its axis and projecting from said forward end of said slide toward said peripheral face with its axis intersecting said peripheral face, a carrier on said slide rotatably supporting said tool holder, said carrier and tool holder having cooperating abutting surfaces to sustain a thrust load imposed axially of said tool holder, and an indexing mechanism for effecting incremental rotation of said tool holder including means operatively connected to said holder to rotate the same and a member relatively fixedly positioned in said assembly in the path of movement of said slide near an end of its traverse and actuating said means upon engagement therewith to operate the same and thereby rotate said tool holder through an increment of rotation.

7. In a grinding wheel assembly including a wheel rotatably mounted about its axis, a guard around said wheel, a slide mounted for reciprocation along said guard in a line of traverse parallel to the axis of said wheel and across the peripheral face thereof, said slide being also mounted for advancement toward and retraction away from said peripheral face and having a forward end facing and proximate to said peripheral face when said slide is advanced and is within that portion of its traversing movement corresponding to the width of said peripheral face, a holder for a diamond tool on said slide mounted for rotation about its axis and projecting from said forward end of said slide toward said peripheral face with its axis intersecting said peripheral face, a carrier on said slide rotatably supporting said tool holder, said carrier and tool holder having cooperating abutting surfaces to sustain a thrust load imposed axially of said tool holder, and an indexing mechanism for effecting incremental rotation of said tool holder including a stop member relatively fixedly positioned in said assembly in the path of movement of said slide and means operatively connected to said holder to rotate the same upon contact with and

actuation by said stop member, such contact occurring when said slide is at an end of its traversing movement and while the diamond tool is beyond an edge of said peripheral face and therefore out of contact therewith.

5 8. In a grinding wheel assembly including a wheel rotatably mounted about its axis, a guard around said wheel, a slide mounted for reciprocation along said guard in a line of traverse parallel to the axis of said wheel and across the peripheral face thereof, said slide being also mounted for advancement toward and retraction away from said peripheral face and having a forward end facing and proximate to said peripheral face when said slide is advanced and is within that portion of its traversing movement corresponding to the width of said peripheral face, a holder for a diamond tool on said slide mounted for rotation about its axis and projecting from 10 said forward end of said slide toward said peripheral face with its axis intersecting said peripheral face, a carrier on said slide rotatably supporting said tool holder, said carrier and tool holder having cooperating abutting surfaces to 15 sustain a thrust load imposed axially of said tool holder, and an indexing mechanism for effecting incremental rotation of said tool holder including a ratchet operatively connected to said holder and a member relatively fixedly positioned in 20 said assembly in the path of movement of said slide and actuating said ratchet upon engagement therewith to effect incremental rotation of said tool holder.
